Inventor

UNITED STATES PATENT OFFICE.

HARRY LE TISSIER BLACKWELL, OF SYDNEY, NEW SOUTH WALES, AUSTRALIA.

GARMENT-STIFFENING DEVICE.

986,895.

Specification of Letters Patent. Patented Mar. 14, 1911.

Application filed October 25, 1909. Serial No. 524,464.

To all whom it may concern:

Be it known that I, HARRY LETISSIER BLACKWELL, a subject of the King of Great Britain, residing at 745½ George street, Sydney, in the State of New South Wales, Commonwealth of Australia, have invented certain new and useful Improvements in Garment-Stiffening Devices, of which the following is a specification.

10 This invention relates to belts including corsets for personal wear and particularly abdominal and "cholera" belts which have at intervals stiffenings of whalebone, steel or the like.

15 The object of my invention is to enable the flexible stiffening pieces to be removed and replaced without the necessity as heretofore, of detaching or opening up the coverings of said pieces, and it further avoids 20 the necessity of resewing the covering after inserting a fresh piece.

My invention consists of a receptacle for the stiffening piece formed by sewing two strips of tape or the like to the belt. These 25 strips are placed side by side in such a manner that their inner longitudinal edges will overlap or meet, said edges when pushed aside permitting the stiffening piece to be inserted into the receptacle on being bent.

30 The ends of said piece are received in pockets produced in the ends of the receptacle. The edges of the intermediate cover or pocket may be held together in any suitable manner at intervals in their length and 35 thereby assist in retaining the stiffening piece in position.

I will now refer to the drawings herewith in which is illustrated the preferred way of carrying out my invention.

40 Figure 1 shows two short lengths of tape or the like, while, Fig. 2 illustrates same stitched together where indicated by the double dotted lines. Fig. 3 shows the material doubled upon itself lengthwise and 45 stitched at the ends, while, Fig. 4 shows the ends formed into pockets when the material is unfolded. Fig. 5 is a reverse view of Fig. 4. Fig. 6 illustrates the manner of inserting a stiffening piece in a receptacle there- 50 for attached to a belt or the like, and, Fig. 7 is a plan of the receptacle with the stiffening piece indicated by dot and dash lines. Fig. 8 is a cross sectional view. Figs. 9 and 55 10 illustrate respectively, plan and perspective views of a belt to which my invention

is applied. Fig. 11 is a perspective view of a corset having my invention applied thereto.

The same numerals indicate the same or corresponding parts.

The receptacle for the stiffening piece is 60 preferably constructed as follows: Two strips 12 of tape or other suitable material are placed side by side in such a manner that their inner longitudinal edges 13 overlap. They are then connected by transverse 65 rows of stitches 14 located adjacent their ends, and by a centrally located similarly arranged row 16, the overlapping edges 13 being then connected by longitudinal rows of stitches 15 which extend from the rows 70 14 to the ends of the strips; (see Fig. 2). The compound strip thus formed is next folded longitudinally upon itself, as shown in Fig. 3, after which its outer corners are stitched together as at 17. When the strip is 75 unfolded, the stitching last referred to will result in the production of a triangular pocket 18 at each end of the strip. The edges of the material thus shaped (Fig. 4) are sewn to a body belt or the like as shown 80 in Figs. 6 and 7 and preferably additional rows of stitching are made at 19 to limit lateral movement of the stiffening piece 20.

To insert a stiffening piece in the receptacle formed on the belt it is only necessary 85 to pull the edges aside and push one end of the said piece into an end pocket (Fig. 6) and then bend the free end so that it will spring into the opposite pocket.

Having thus described my invention, what 90 I claim as new and desire to protect by Letters Patent is:—

1. As a new article of manufacture, a stiffening device adapted to be attached to a body belt or the like comprising a receptacle, and a stiffening piece disposed therein, said receptacle consisting of a pair of strips of fabric arranged side by side and having their presented longitudinal edges overlapping and their outer corners turned 95 inwardly and stitched to the adjacent portions of said strips to produce pockets wherein the ends of said stiffening piece are received.

2. As a new article of manufacture, a 105 stiffening device adapted to be attached to a body belt or the like comprising a receptacle, and a stiffening piece disposed therein, said receptacle consisting of a pair of strips of fabric arranged side by side and 110

having their presented longitudinal edges overlapping, and their outer corners turned inwardly and stitched to the adjacent portions of said strips to produce pockets where-
5 in the ends of said stiffening piece are received, said strips being connected together by spaced transverse rows of stitches, to maintain said overlapping edges normally closed.

In testimony whereof I have hereunto set 10
my hand in presence of two subscribing
witnesses.

HARRY LE TISSIER BLACKWELL.
